PICTURE AND MIRROR HOLDER

Filed July 30, 1951

Fig. 1

UNITED STATES PATENT OFFICE

2,632,971

PICTURE AND MIRROR HOLDER

Cashman Manczek, Aberdeen, Wash., and Eric K. Lotthammer, Jamaica, N. Y.; said Lotthammer assignor to said Manczek

Application July 30, 1951, Serial No. 239,326

1 Claim. (Cl. 40—155)

1

This invention relates to a support or holder for a picture or mirror.

The object of this invention is to provide a support by means of which a picture may be held and supported in proper position to be placed on a flat surface such as a piece of furniture or mantelpiece.

Another object of this invention is to provide an adjustable support which may be adjusted to grip and to support pictures of various dimensions, or mirrors of corresponding dimensions, for disposition on a flat table support, or to be suitably suspended from a nail, a bracket or molding.

Another object of this invention is to provide a picture and mirror holder that shall be relatively simple in construction, economical to manufacture, and that shall be easy to apply and to remove from pictures or mirrors of different sizes.

The construction and operation of the combination picture and mirror holder of this invention will be more readily understood upon reference to the accompanying description and drawings, in which:

Fig. 1 is an elevational view of the picture holder as viewed from the rear of a picture upon which the holder is welded;

Fig. 2 is a sectional view of the structure shown in Fig. 1 taken on the diagonal line 2—2 of Fig. 1;

Fig. 3 is a sectional view taken through one arm of the holder in Fig. 1, taken on line 3—3 in the direction indicated;

Fig. 4 is a perspective exploded view of the locking and supporting elements of the structure at the middle of the frame;

Fig. 5 is a side elevational view of a picture or mirror element in supported position in the holder on a flat surface; and

Fig. 6 is a front perspective view of a corner of a mirror supported by the holder to show the manner in which one of the finger brackets grips the outer edge of the mirror.

As shown in Fig. 1, a picture or mirror 10, indicated in broken line for simplicity of illustration, is held by a supporting frame or holder 11 of X-shape 11, consisting of four cross arms 12, 13, 14 and 15 respectively, each of which supports and guides an extension arm 16, 17, 18 and 19, respectively. Each of the extension arms 16 to 19 inclusive, pivotally supports a finger bracket 20 that fits over the edge of the picture or mirror that is to be supported, and thereby serves to hold the picture or mirror in place, between two oppositely disposed pairs of brackets 20.

The construction of the bracket 20 is shown

more fully in Fig. 2, as consisting of a body of short section having an arcuate outer surface 21, a longitudinal slot 22 extending downwardly into the body of the bracket 20 below an upper surface 23. The slot 22 is made wide enough to accommodate any thickness of mirror or picture that would ordinarily be encountered, and any additional space that remains may be taken up by a suitable backing card 24 and a short filler strip 25. A short pin 26 provides the pivotal connection between the bracket 20 and the supporting extension arm 18.

Once the holder is assembled on a picture or mirror it is held tightly in place by the combined action of a tension spring 27 in each of the two upper arms 12 and 13 and respectively anchored at one end to a lug 28 at the inner end of each of the extension arms 16 and 17, and anchored at the other end on a center assembling screw 30.

The manner in which the holder is assembled into a rigid supporting unit may be clearly seen upon reference to Fig. 4. As there shown, the inner ends of the cross arms 13, 12, 14 and 15 may be formed to embody the peripheral groove 32 to serve as seats for correspondingly shaped arcuate portions 33 and 34 on the flanged rims 35 and 36 of two cooperating cups 37 and 38.

Two locking cups 37 and 38 each consist of a main body portion and a rim flange. Each rim flange is provided with the four cut out portions 33, 34, disposed at right angles, in order to permit the two cups to be fitted so the cut out portions will seat in the grooves 32 at the inner ends of the main arms and grip those inner ends of those main arms against relative rotation or displacement. The two caps 37 and 38 are held tightly together by a lock screw combination consisting of internally threaded ferrule 39 and a small bolt 40 which threads into the ferrule 39 and pulls it tightly to clamp the two cups 37 and 38 together. Appropriately sized openings 41 and 42 are provided in the two cups 37 and 38 to accommodate the ferrule 39 and the bolt 40.

As previously indicated, the tension spring 27 is disposed in each of the upper arms 12 and 13, with the upper end of each spring 27 anchored on a lug 28 at the lower end of the extension arms 16 and 17. The lower end of each of the two tension springs is formed into a loop 43 which is fitted around the ferrule 39 and anchored thereon in order to put the springs 27 under tension and the extension arms 16 and 17 are pulled out far enough to enable the brackets 20 to be fitted

over the upper edges of the picture or mirror 10. The adjustment of the lower extension arms 18 and 19 is achieved by means of adjusting cords 45 and 46, the inner ends of which are secured to the lugs 28 on the inner ends of the tension arms 18 and 19 at the bottom of the frame. Those cords may be tied to the lugs in any suitable manner, being indicated in Fig. 2, as anchored against movement by the formation of a knot 47 at the end of the tied cord 45.

The cap 38 is provided with two openings 48 and 49 through which the two tie cords 45 and 46 may be brought out from within the hollow arm 14 and the bracket 38. The cup 38 is further provided with three bridging loops 51, 52 and 53, that are pressed from the base metal of the cup. The two outer loops 51 and 53 serve to guide the two tie cords 45 and 46 after they exit from the cup 38. The three loops 51, 52 and 53 then serve as retainers to receive and hold correspondingly positioned fingers 55 of a bracing bracket 56 provided with an adjustable extension 57 and a locking thumb nut 58 to permit the mirror or picture holder to be angularly adjusted with respect to a horizontal supporting surface 59 upon which the mirror may be supported.

After the two tie cords 45 and 46 pass upward through the guide loops 51 and 53, they extend along the length of the two arms 12 and 13 respectively and then through corresponding tunnel brackets 61 and 62 that are respectively secured to their associated arms 12 and 13 respectively, in any suitable manner and by spot welding.

After the two tie cords 45 and 46 are threaded through their respective tunnel brackets 61 and 62 they may be tied to each other to take up any slack, or the respective ends may then be threaded through the small opening 63 or 64 in the respective tunnel brackets 61 or 62, and then knotted, so any slack remaining in the two tie cords will be pulled back into their respective cross arms out of the tension of the two tension springs 27, which will tend to raise the two center cups to a higher elevation.

By means of the construction illustrated, a very simple mirror and picture support is provided which may be utilized to support a picture or mirror on a flat surface, or, when suspended to support the picture or mirror on a wall.

The invention is not necessarily limited to the exact details of construction that are shown, since various modifications may be made therein without departing from the spirit and scope of 10 the invention as set forth in the appended claim.

What is claimed is:

A picture holder comprising four (4) arms to constitute an X-frame, a center bracket embracing the inner ends of the arms and consisting of two circular flanged cups to be coaxially disposed to face each other to grip the inner ends of the arms between the cup flanges, with an axial locking screw to hold the two cups together in position to grip the inner ends of the arms tightly, an extension bar slideably supported on each arm, a tension spring for each upper extension bar with one end of the spring anchored on the extension bar and the other end of the spring anchored on the axial locking screw, a flexible cord carried by said center bracket and connected to each lower extension bar for adjustably positioning each lower extension bar, and a clamp on each extension bar to grip a picture edge.
